UNITED STATES PATENT OFFICE

2,525,259

NECKTIE RACK

August Fenzl, Chicago, Ill.

Application March 17, 1947, Serial No. 735,080

4 Claims. (Cl. 211—124)

1

My invention relates generally to racks for neckties, and more particularly to a rack of this type in which the ties are held from slipping and falling from the rack.

In ordinary tie racks, difficulty is experienced in preventing the ties from slipping from the support. It is therefore the primary object of my invention to provide an improved tie rack comprising a pair of tie supporting rods and an additional pivoted rod by which a force may be applied to the portions of the ties extending between the fixed rods, so as to introduce additional bights in the ties and thereby greatly increase the friction between the ties and these rods so as to prevent them from slipping therefrom.

A further object is to provide a tie rack which is simple in construction, neat in appearance, and upon which the ties may be easily placed and removed.

Other objects will appear from the following description, reference being had to the accompanying drawings, in which

Fig. 1 is a perspective view of the complete tie rack illustrating particularly its manner of use;

Fig. 2 is a left end elevation of the tie rack;

Fig. 3 is a sectional view of a tie rack, taken on the line 3—3 of Fig. 1;

Fig. 4 is a fragmentary sectional view, taken on the line 4—4 of Fig. 1; and

Fig. 5 is a fragmentary perspective view of the pivotal connection of the movable rod and left-hand bracket, shown to an enlarged scale.

The tie rack comprises a pair of brackets 10 and 12, having flanges 14 provided with holes for securing the bracket to a suitable support. In Fig. 1, the support is illustrated as a suitably finished board 16 which may in turn be secured to a wall, door, or article of furniture in any manner desired. In other instances the brackets 10 and 12 may be directly secured to the supporting wall or door.

The brackets 10 and 12 are joined by a pair of fixed necktie supporting rods 18 and 19 which are spaced from one another and extend in parallel relation in a substantially horizontal plane. The ends of these rods are fixed to the brackets 10 and 12 by any suitable means, such as by screws 20 threaded in the ends of the rods, suitable washers 22 being interposed between the ends of the rods and the brackets, as illustrated in the enlarged view of Fig. 4.

The bracket 10 is provided with a vertical elongated slot 24 which is bridged near its lower end by a pivot portion 26. A pressure rod 28 has

2

a keyhole slot 30 formed in the end thereof, the narrow portion of this slot being of slightly greater width than the thickness of the bracket 10, while the cylindrical portion of the slot is of sufficient diameter to accommodate the pivot portion 26 and to permit the rod to pivot freely thereon.

As best shown in Fig. 3, the bracket 12 is provided with a wide mouthed slot 32 which extends downwardly from the upper edge of the bracket and at its lower end has an upwardly turned locking portion 34.

In using the rack, the pressure rod 28 is swung upwardly through the slot 32 about its pivot 26 to a diagonal or vertical position, as indicated by the dot-dash lines in Fig. 1, and the ties to be supported are placed across the rods 18 and 19, the portions of the ties resting between the bars 18 and 19 being initially horizontal, as indicated by the tie shown in dotted lines in Fig. 1. After the ties have been placed upon the rack, the pressure rod 28 is swung downwardly and then upwardly into the notch 34. In doing so, the pressure rod flexes the portions of the ties intermediate the rods 18 and 19 to cause them to assume the shapes indicated by the ties 36 shown in full lines in Fig. 1. When in this position, the frictional forces between the ties and the rods 18, 19, and 28 is greatly increased by virtue of the increase in areas of contact between the ties and the rods 18 and 19, and because of the added friction between the ties and the pressure rod 28. The pressure rod, in pressing the center portions of the ties downwardly as described, also places the portions of the ties between the rods 18 and 19 under slight tension, which also is a factor in providing increased friction of the ties against the rods. The weight of a few ties on the rack is sufficient to hold the rod 28 in the locking portion 34 of the slot 32.

Whenever it is desired to remove any tie from the rack, it may easily be done merely by grasping the depending forward end of the tie and pulling upwardly, holding the adjacent ties against movement. The ties may be overlapped as indicated by the ties shown in solid lines in Fig. 1, and the capacity of the rack is therefore very great, considering the length of the rods.

If desired, the ends of the pressure rod 28 adjacent the keyhole slot 30 may be bent toward each other slightly after having been passed over the pivot 26, so as permanently to attach the pressure rod 28 to the bracket and prevent it from being lifted from the bracket 10 when the rod is raised to its vertical position.

While I have shown and described a preferred

embodiment of my invention, it will be apparent that numerous variations and modifications thereof may be made without departing from the underlying principles of the invention. I therefore desire, by the following claims, to include within the scope of the invention, all such variations and modifications by which substantially the results of my invention may be obtained through the use of substantially the same or equivalent means.

I claim:

1. A necktie rack comprising a pair of horizontally spaced brackets constructed for rigid attachment to a support, a pair of tie supporting rods joining said brackets, said rods being parallel and spaced from one another in a substantially horizontal plane, a pressure rod loosely pivoted to one of the brackets at a point beneath and between the points at which the other rods are joined to the bracket, and means on the other bracket for releasably holding the pressure rod in horizontal position when it is subjected to an upwardly directed force tending to pivot it to a vertical position and arranged to permit such upward pivotal movement when manually released.

2. A rack for holding neckties comprising a pair of horizontally spaced brackets, a pair of parallel horizontal necktie supporting rods secured at their ends to said brackets, a pressure rod pivoted on one of the brackets at a point intermediate and below the points at which the other rods are secured to the bracket, and means on the other bracket releasably to hold the free end of the pressure rod in substantially horizontal position thereby to press downwardly on neckties hung over the supporting rods and increase the friction holding the neckties from slipping from the rods.

3. A rack for neckties comprising a pair of horizontally spaced brackets, a pair of spaced horizontal parallel rods secured at their ends to the brackets, and a pressure rod pivoted to one of the brackets at a point intermediate the points at which the other rods are secured to the bracket, the other bracket having an open end J-shaped slot therein for the reception of the free end of the pressure rod whereby the pressure rod may be held against upward movement when pressed against neckties hung over the other rods.

4. A rack for holding neckties comprising a pair of horizontally spaced brackets, a pair of parallel horizontal necktie supporting rods secured at their ends to said brackets, a pressure rod pivoted on one of the brackets at a point intermediate and at one side of the plane defined by the parallel rods and swingable through said plane, and means on the other bracket releasably to hold the free end of the pressure rod in substantially horizontal position thereby to press against neckties hung over the supporting rods and thus to increase the friction holding the neckties from slipping from the rods.

AUGUST FENZL.
